[57] CLAIM

The ornamental design for an apparatus for peeling vegetables, as shown and described.

DESCRIPTION

FIG. 1 is a front perspective view of an apparatus for peeling vegetables showing our new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof; and,

FIG. 7 is a view similar to FIG. 5, showing the apparatus in open position.
